UNITED STATES PATENT OFFICE.

WILLIAM C. ALLISON AND JOHN HOSKIN, OF PHILADELPHIA, PA.

APPARATUS FOR ESTABLISHING PERMANENT CHANNELS IN RIVERS, &c.

SPECIFICATION forming part of Letters Patent No. 231,698, dated August 31, 1880.

Application filed June 11, 1880. (No model.)

To all whom it may concern:

Be it known that we, WILLIAM C. ALLISON and JOHN HOSKIN, of the city of Philadelphia, in the county of Philadelphia and State of 5 Pennsylvania, have invented an Improvement in Apparatus for Establishing Permanent Channels in Rivers, Sand-Bars, &c., of which the following is a specification.

Our invention relates to apparatus or flumes 10 designed to deepen water-channels or establish a permanent channel in rivers, sand-bars, &c.; and our invention consists in constructing a flume in such a manner that the flow of water under pressure in the main is under perfect 15 control, and can be brought to operate upon the sand-bar, &c., at any point desired; further, in the combination of a water-main or flume with one or more jet-pipes rigidly or flexibly attached to said main, and their communication 20 controlled by suitable cocks or valves, whereby any section or sections of the jet-pipes may be shut off and made independent of those remaining; further, in furnishing the water-main with suitable valves along its 25 length, for the purpose of allowing one part of the pipe to be repaired while the other part is at work; further, in providing the water-main or flume with auxiliary outlets, in combination with valves, for the purpose of allowing a pump 30 to be attached and allow any section of the flume to be used separately and independently of the head of water at the end; and, finally, in attaching such a flume to a boat, or supporting it upon a float before said boat, and 35 operating it to form a channel through a bar in a river and allow the passage of the boat.

Heretofore flumes have been made of a single pipe or main provided with holes at the bottom and without valves to control the flow 40 from the holes, or they have been made with a slide plate or valve perforated and made to fit the bottom of this single flume or main; but the valve was not tight, as it was impossible to make a good fit or close contact between the 45 surfaces of the main and slide; and, further, in both of these cases the sand worked itself into the water-main, and in the latter case would not allow the valve or slide to work.

In the former case, if the pipe or flume were 50 long, there would be no pressure in the end sections, since the water would have run out of

the perforations nearer the head or pressure end. This is almost equally so of the latter construction, since the construction of valves referred to will not prevent the leakage of sufficient water to allow the engineer to control the flow in a great length of pipe; further, in the single pipe or flume, if it be in a considerable length, it is liable to turn or twist, allowing the jets to play laterally, which is very objectionable.

With our improvement we overcome all of these difficulties, and the construction of our apparatus is fully set forth in the following specification, shown in the accompanying drawings, and referred to in the appended claims.

In the drawings, Figure 1 is an end view or cross-section of one form of our improved combination-flume in which there is one jet-pipe. Fig. 2 is a plan of a short length of same. Fig. 3 is a cross-section of same, only with two jet-pipes. Fig. 4 is a plan of same. Fig. 5 shows detailed views of the jet-pipe and the method of setting the holes. Fig. 6 is a cross-section of a modified form of Fig. 3. Fig. 7 is a plan 75 view of a modified form of Fig. 3, being more compact. Fig. 8 is a side elevation of same. Fig. 9 is a cross-section of same. Fig. 10 is an end view, having a single jet-pipe, and the valves to each section thereof arranged alternately on each side of the water-main or flume 80 to balance it. Fig. 11 is a side elevation of same. Fig. 12 is an end view of a modified form of same, in which the valves are located within the main or flume and in the central 85 vertical line. Fig. 13 is a side elevation of same. Fig. 14 is a modified form of that shown in Fig. 9. Fig. 15 is a plan of same. Fig. 16 shows the flume attached to a boat arranged to clear an obstructed channel.

In all of these forms of our invention, A is the water-main or flume proper, and is made in sections and connected by suitable couplings E and D', which also join and support the jet-pipes B. These jet-pipes are perforated with 95 small holes arranged in one or more rows, and covering an area of about one-quarter the superficial area of the pipe, as shown in all the cross-sections and Fig. 5.

The main or flume A has no perforations, as 100 in former constructions, but has communication with the jet-pipes B through the couplings

E, which communication is governed by a suitable valve, C. The ends of the jet-pipes B are supported and their ends closed by a solid socket, D, which may be cast with the coupling D', as shown in Fig. 15, or made separate, as shown in Fig. 4.

It is not necessary to our invention that the jet-pipes are screwed directly into the coupling, and that the said coupling shall contain the valves, since the said pipes may be connected to the coupling or valve in same by an independent T-piece, as shown in Fig. 4, or by several elbows and T-pieces, as shown in Fig. 6, and the valves may be simple pipe-cocks screwed on the ends of the jet-pipes and independent of the couplings E, as shown in Figs. 14 and 15. The construction shown in these two figures is that which I prefer, on account of simplicity, efficiency, and cheapness.

15 The advantage of having two jet-pipes, B, is apparent from an examination of the several drawings, from which it is seen that a flume or water-main provided with a jet-pipe, B, arranged on either side, as shown in Fig. 15, is perfectly balanced, and would always remain in a normal position upon the bed of sand, silt, &c. The holes b b in the jet-pipes B are so directed that they throw part of the water under the flume or main A, and thereby wash away its support, causing the combined flume to change its bevel of base or bed, and at the same time cutting a channel in the sand.

At various points along the length of the main or flume A, and at its end, are valves F and openings N, provided with covers, (shown in dotted lines in Fig. 2,) for the purpose of cleaning out the flume, allowing repairs, or allowing any section of the flume to be used independently by closing-valves F and attaching a pump at an opening, N, and forcing water into the main A at that point, thereby using that part of the apparatus only which rests upon a bar to be removed. When a flume or jet-pipe, K, is attached to a vessel or floating body, H, it is so arranged in front of the vessel that it can be raised or lowered to any required depth at will, and is connected to a force or other pump, I, by a flexible pipe, J. By making the flume part of the equipment of vessels plying in muddy or shallow waters whose channels are liable to become filled, channel could be cut or made through any sand-bar upon which the said vessel may run aground, and allow her to float again.

The operation is as follows: The combined flume being laid in position along the bed of a river, sand-bar, or shallow water in which it is desired to cut and keep open a permanent channel, one end is connected with a dam or pump, through the agency of which water is forced under pressure through the water-main or flume A, the valve F at the other end being closed. If at any point the flume rests upon a sand-bar, and it is to be removed, the valves C, controlling the supply of water to the jet-

pipes B at such place, are opened and the communication between the main A and jet-pipes B at that point is made free, and the water under pressure passes from the main 70 into the jet-pipes, and from these pipes, in small jets or streams, against the sand, mud, silt, &c., which, moving under pressure, loosens the obstruction, and it is then carried away by the current of the river or the artificial current produced in still waters by the flume. As the channel is thus deepened the combined flume sinks with it, constantly cutting deeper and deeper.

If desired, all the jet-pipes arranged on 80 either side of the flume or under it can be made to throw out jets of water if solid material along its entire bed is to be removed; but if the flume crosses clear water at any point, then to open the valves C would be mere 85 waste of water and pressure, so at that point they would be kept closed. Thus a line of channel may be opened, into which the water sluggishly flowing over the adjacent shallows will then flow with increasing rapidity, as the 90 whole of the current finds its way into it, carrying by the increased rapidity the silt that lately choked the channel, and thereby deepening it. The apparatus cuts a channel, and thereby causes the river to be its own silt-carrier.

If it is found more practicable in any particular operation to make the jet-pipes B flexibly attached to the main or flume A, so that the former alone need rest on the bottom, bar, 100 &c., while the flume or main itself may be on shore, it can be so constructed without departing from our invention.

Having now described our invention, what we claim as new, and desire to secure by Letters Patent, is—

1. In a combined flume, a water-main to supply water under pressure, sections of jet-pipes connected and communicating with said main, and suitable valves to govern the supply of water to any section or sections of jet-pipe, substantially as and for the purpose specified.

2. In a flume, a water-main one end of which is in communication with a head of water under pressure, provided with valves along its length to prevent the flow of water beyond a given point during repairs, &c., substantially as and for the purpose specified.

3. In a combined flume, a flume or main, A, 120 jet-pipes B, provided with small holes b, couplings E, valves C, and sockets D, combined substantially as and for the purpose specified.

4. In a combined flume, a flume or main, A, jet-pipes B, provided with holes b, couplings E, valves C, and combined coupling and socket D' D, all arranged substantially as and for the purpose specified.

5. In a flume, a water-main, A, jet-pipe B, having holes b, valves C and F, all combined substantially as and for the purpose specified.

6. Apparatus for deepening channels and

removing sand-bars, consisting of a horizontal, or nearly horizontal, flume having the end substantially closed, and provided with holes or an equivalent device, as set forth, to throw out jets of water under pressure along its length, said flume being flexibly attached to a boat or its appendage, in combination with said boat, and a force-pump or its equivalent, by which water is forced under pressure into the flume, substantially as and for the purpose specified.

7. In a flume for washing out sand-bars, &c.,

a main, A, provided with valves F at intervals along its length, and openings N, provided with a cover, one of which is placed between any two valves F, all combined substantially as and for the purpose specified. 15

In testimony of which invention we hereunto set our hands.

W. C. ALLISON.
JOHN HOSKIN.
